UNITED STATES PATENT OFFICE.

THOMAS RUTHERFORD MACMECHEN AND EDWIN MARSHALL FOX, OF WESTMINSTER,
LONDON, ENGLAND.

AIRSHIP OR DIRIGIBLE BALLOON.

1,219,121.

Specification of Letters Patent. Patented Mar. 13, 1917.

Application filed December 1, 1915. Serial No. 64,530.

To all whom it may concern:

Be it known that we, THOMAS RUTHERFORD MACMECHEN, a citizen of the United States of America, and EDWIN MARSHALL Fox, a subject of the King of Great Britain, residing at 66 Victoria street, Westminster, in the county of London, England, have invented certain new and useful Improvements in or Relating to Airships or Dirigible Balloons, of which the following is a specification.

This invention relates to airships or dirigible balloons, the chief object being to enable their buoyancy to be readily controlled within wide limits without having to resort to the use of ballast as heretofore. It has previously been proposed to render the buoyancy of airships and dirigible balloons of a uniform character, by passing a current of air of the same temperature as the external atmosphere between the gas bags or compartments and the envelop of the body portion thereof but such arrangement does not provide for the buoyancy to be varied for purposes of ascent and descent.

According to this invention the desired control of the buoyancy is obtained by varying the temperature of the air or gaseous medium and causing the same to swirl around the gas bags or compartments of the body portion of the airship. With this object in view the air or gaseous medium may be caused to pass through spiral passages of the character disclosed in the specification of prior Patent No. 1,108,113, which are formed in the space between the gas bags or compartments and the envelop of the body portion of the airship. The desired variation of temperature is effected by utilizing the heat in the products of combustion from the internal combustion engine or motor or other source of power provided for propelling the airship. In order to attain the latter object the means provided for forcing the current of air around the gas bags or compartments of the airship are adapted to force more or less of the products of combustion from the internal combustion engine around the gas bags when the temperature of the gas therein is to be varied.

In order that the said invention may be clearly understood and readily carried into effect we will proceed to describe the same

more fully with reference to the accompanying drawings in which:

Figure 1 is a side elevation of an apparatus for carrying the invention into effect.

Fig. 2 is an end elevation of the said apparatus.

Fig. 3 is a plan thereof, and Fig. 4 is a sectional detail view thereof.

The means employed for controlling the flow of the gaseous medium around the gas bags or compartments of the airship may comprise a rotary fan or blower *a* arranged in a casing *b* conveniently mounted on the airship. The casing *b* is provided with an outlet branch *b'* leading to the space around the gas bags of the airship and an inlet pipe *b''* having three rectangular branches *b²*, *b³* and *b⁰*. The branches *b³* and *b⁰* open into the atmosphere whereas the other branch *b²* is connected to a chamber or exhaust box *b⁴* pertaining to the motor *c*. Each of the branches *b²* and *b³* is adapted to be controlled by a common valve or damper *b⁵* for rendering the same wholly or partially operative or inoperative as may be desired.

The damper *b⁵* is mounted on a spindle *b⁶* which is provided with an operating lever *b⁷* and suitably mounted in a bracket or the like *b⁸* attached to the chamber or exhaust box *b⁴*. Another spindle *b⁹* is arranged adjacent to the spindle *b⁶* and is suitably connected or linked thereto so as to be actuated with the spindle *b⁶* when the latter is angularly displaced by means of the lever *b⁷*. The spindle *b⁹* carries a damper *b¹⁰* which is adapted to open or close the branch *b⁰* and which is operated simultaneously with the damper *b⁵*.

b¹¹ is the exhaust pipe from the engine *c* and it leads to the aforesaid chamber or exhaust box *b⁴*. The two dampers *b⁵* and *b¹⁰* carried by the angularly displaceable spindles *b⁶* and *b⁹* are so disposed that when the damper *b⁵* is closing the branch *b³* the damper *b¹⁰* will be closing the branch *b⁰*. Consequently the branches *b³* and *b⁰* will always be in the same condition either closed or opened.

The other inlet branch *b²* of the fan will be open when the branches *b³* and *b⁰* are closed and will be closed by the damper *b⁵* when the said branches are open. The respective positions of the dampers *b⁵* and *b¹⁰* are shown in full and broken lines in Fig.

3. When the dampers are in the position shown in full lines the products of combustion from the exhaust box b^4 will pass to the fan, whereas when the dampers are in 5 the other position the products will pass to the atmosphere through the branch b^6 and cool air will be admitted to the fan through the branch b^3 . It will be seen therefore that the fan casing b may be readily placed in 10 connection with the exhaust box b^4 or the external atmosphere according as it is desired to pass a hot or cool current of gaseous medium around the gas bags or compartments of the airship. The chamber or exhaust box b^4 which is connected to the motor by the pipe b^{11} may be provided with suitable asbestos or other screens d^2 or a baffle d^3 to prevent the passage of hot particles of soot or sparks and thereby avoid 15 danger of injury to the gas bags or compartments of the air ship. The exhaust box may also be provided with a lining d^4 of asbestos or other suitable material.

The fan or blower a is driven by the motor 20 c of the airship through belting or other suitable transmitting gear c' and when the aforesaid dampers are appropriately set, is adapted to force the products of combustion from the said motor or a current of air from 25 the surrounding atmosphere around the gas bags or compartments of the airship to control the buoyancy thereof.

What we claim and desire to secure by Letters Patent of the United States is:—

- 35 1. In an airship or dirigible balloon, the combination with apparatus for forcing cool and heated media around the gas bags or compartments of the airship, for buoyancy control, of means for regulating the relative proportions of said media and for excluding one while admitting the other.
- 40 2. In an airship or dirigible balloon, the combination with a propelling engine, of apparatus for forcing cool and heated media around the gas bags or compartments of the airship, for buoyancy control, and means
- 45

for regulating the relative proportions of said media and for excluding one while admitting the other.

3. In an airship or dirigible balloon, the 50 combination with a propelling engine, of apparatus for forcing air and the heated products of combustion from the engine around the gas bags or compartments of the airship, and means for proportionately varying the relative quantities of said media.

4. In an airship or dirigible balloon, the combination with a propelling engine of a rotary fan, a casing for said rotary fan, inlet branches thereon communicating with the engine exhaust and the atmosphere and dampers for controlling said inlet branches to vary the temperature of the air or gaseous media forced by the said fan around the gas bags or compartments of the airship.

5. In an airship or dirigible balloon, the combination with a propelling engine of an exhaust box, a blower, an inlet pipe on said blower having a number of branches which 70 communicate respectively with the said exhaust box and the atmosphere and a system of inter-connected dampers for controlling said inlet branches and thereby varying the temperature of the air or gaseous media 75 forced by the blower around the gas bags or compartments of the airship.

6. In an airship or dirigible balloon, the combination with a propelling engine of an exhaust box, screens or baffles in said box, 80 a rotary fan, a casing for said rotary fan, an inlet pipe on said casing having a number of branches which communicate respectively with the said exhaust box and the atmosphere and a system of inter-connected 85 dampers for controlling said inlet branches and thereby varying the temperature of the air or gaseous media forced by the fan around the gas bags or compartments of the airship.

THOS. RUTHERFORD MACMECHEN.
EDWIN MARSHALL FOX.
